HINGE

La Verne E. Clayton, % Amerock Corporation,
4000 Auburn St., Rockford, Ill. 61103

Original design application June 12, 1967, Ser. No. 7,436,
now Patent No. 209,815, dated Jan. 9, 1968. Divided
and this application Sept. 25, 1967, Ser. No. 8,716

Term of patent 14 years

(Cl. D10—9)

FIGURE 1 is a front elevational view of a hinge, incorporating my new design.

FIG. 2 is an enlarged top view of the hinge.

FIG. 3 is an enlarged sectional view of the hinge taken along the line 3—3 in FIG. 1.

FIG. 4 is a side view as seen from the left in FIG. 1.

FIG. 5 is a perspective view of the hinge.

FIG. 6 is a front elevational view of a modified form of the hinge.

FIG. 7 is an enlarged top view of the hinge shown in FIG. 6.

FIG. 8 is an enlarged sectional view taken along the line 8—8 in FIG. 6.

FIG. 9 is a side view as seen from the left in FIG. 6.

FIG. 10 is a perspective view of the hinge shown in FIG. 6.

This application is a division of my copending design application Ser. No. 7,436, filed June 12, 1967, and now Patent Number D.209,815.

I claim:

The ornamental design for a hinge, as shown and described.
